[57] CLAIM

The ornamental design for a siphon wand kit for use with aquariums and tanks, as shown and described.

DESCRIPTION

FIG. 1 is a front elevational view of the siphon wand kit for use with aquariums and tanks showing my new design;
FIG. 2 is a rear elevational view thereof;
FIG. 3 is a right side view thereof;
FIG. 4 is a left side view thereof;
FIG. 5 is a top plan view thereof; and,
FIG. 6 is a bottom plan view thereof.

The claimed design is shown fragmented in FIGS. 1-4 to indicate indeterminate length.
